UNITED STATES PATENT OFFICE.

WILLIAM H. GOLDSMITH AND STEPHEN M. HAMBLIN, OF CENTRAL FALLS,
RHODE ISLAND.

SPINNING-SPINDLE.

SPECIFICATION forming part of Letters Patent No. 671,694, dated April 9, 1901.

Application filed October 22, 1900. Serial No. 33,806. (No model.)

To all whom it may concern:

Be it known that we, WILLIAM H. GOLDSMITH and STEPHEN M. HAMBLIN, citizens of the United States, residing at Central Falls, 5 in the county of Providence, State of Rhode Island, have invented a certain new and useful Improvement in Spinning-Spindles, of which the following is a specification, reference being had therein to the accompanying drawings.

10 Figure 1 of the drawings shows, partly in elevation and partly in section, an embodiment of our invention. Figs. 2 to 5 show modifications.

Our invention consists, mainly, in forming 15 a spinning-spindle in two parts, one of such parts, termed by us the "whirl" part, being provided in practice with a suitable bearing in a spinning-frame and remaining permanently associated with the said bearing in the 20 said spinning-frame, and the other of such parts being termed the "skewer," it being in the shape of a detachable spindle-blade and being adapted to be applied to and connected with the whirl part to rotate in unison with 25 the latter during the spinning operation and to receive the yarn load, the said skewer being adapted to be detached from the whirl part after having been fully loaded with yarn, it being especially constructed with reference 30 to enabling it to be placed directly into a shuttle for weaving the said detachable skewer, taking in the shuttle the place of the usual spindle, which last is dispensed with.

Having reference to the drawings, 1 designates the whirl part of our improved spindle. 35 The whirl thereof is designated 2. The said whirl part 1 is or may be in practice constructed like the whirl and lower or bearing part of any of the approved makes of spindles. Herein it is shown constructed with a downwardly-extending cylindrical foot portion 3 below the whirl 2, corresponding substantially in shape with the foot portions of spindles now in use, the said foot portion 3 being fitted within an external bearing 4 in a bearing-support 5, the said bearing-support being secured in a hole of the spindle-rail 6 by means of a nut 7 upon the threaded lower end 8 of the said bearing-support in customary manner. 9 designates the usual hook or 45 detent for preventing the whirl part 1 from

becoming accidentally lifted out of the bearing of the bearing-support. The said whirl part 1 is made hollow or tubular to form an elongated cylindrical central chamber to receive the lower end of the skewer 10. The said skewer may in practice be formed of any suitable material, but preferably is made of wood for the sake of cheapness and of lightness, which last is of especial importance when 55 the skewer, with its load of yarn, is placed in a shuttle in order that the said load of yarn may be utilized as weft in weaving cloth. The shape of the interengaging portions of the whirl part and skewer may be varied more 60 or less, although preferably we form a tapering bore 11 within the whirl part and correspondingly taper the portion 12 of the skewer which enters the said bore. The fit of the end of the skewer within the bore of the whirl 65 part secures the requisite frictional adhesion for causing the skewer to rotate in unison with the whirl part during the operation of spinning. If desired, we may increase the said frictional adhesion by slitting the end of the 70 skewer, as at 14 in Fig. 2, in which case the elasticity of the portions of the skewer end which are separated by the slit will be brought into play by the compression which occurs 75 when the skewer end is forced home into the bore of the whirl part. In this case the skewer end will be made a little larger relatively to the diameter of the bore of the whirl part, so as to insure the bending of the said parts of the skewer end toward each other as the 80 skewer end is caused to enter the bore of the whirl part. When the skewer end is slotted, as just described, the said skewer end need not be tapered and may be left cylindrical, as 85 shown in Fig. 2. 90

In some cases we may provide a positive lock for compelling the skewer to rotate in unison with the whirl part. Thus in Fig. 3 we have shown a wire or screw 15, driven across the inner part of the bore of the whirl part, 95 the end of the skewer being notched, as at 16, to fit over the said wire or screw. The flat side of the notch fits against the side of the said wire or screw.

In some cases we may employ a yielding clip 100 or pressure device to prevent the skewer from rising within the whirl part and becoming

loose with reference thereto. Thus in Fig. 4 we have shown a split ring 17, seated within an internal groove 18, formed in the whirl part. When the skewer end is pushed into the bore of the whirl part, it preferably expands the said split ring which clamps the skewer end firmly. This device prevents the skewer from coming loose at high speeds of rotation.

10 Fig. 5 shows a form of the invention in which the whirl part is provided above the whirl with an extension 19, which is slotted, as at 20, to form a series of elastic tongues. The series of elastic tongues constitute a yielding-15 clamp to hold the skewer in place.

Preferably we form the skewer double ended, as in Fig. 1—that is to say, it is symmetrical, both ends being alike, so that either end may be entered indifferently into the 20 whirl part, according as the skewer may happen to be picked up for the purpose of being applied to the whirl part. The skewer is slightly barrel shape—that is to say, is largest in diameter at about mid-length thereof and 25 gradually contracts in diameter therefrom to the entering ends. The barrel shape of the skewer eliminates tendency of the same to warp, while the double-ended construction extends its period of service, since notwithstanding 30 either end of the skewer may become injured the skewer may still be continued in use so long as the other end thereof remains in good shape.

For the purpose of permitting the air confined 35 in the whirl part to escape as the skewer is being inserted into the bore of the latter and pressed home, we form a groove leading to the outer end of said bore in the inner surface of the said whirl part. This groove 40 either may extend straight along said bore, as at 24, Fig. 4, or spirally, as at 25, Fig. 5. The escape of the air which is permitted by the said groove obviates tendency of the skewer to become forced upward and loosened 45 in its seat within the whirl part by expansion of said air when the whirl part becomes warm in operation.

We claim as our invention—

1. In combination, in a spinning-machine, 50 the whirl part having a downwardly-extending cylindrical portion containing an elongated cylindrical central chamber, an external bearing receiving the said cylindrical portion, and the skewer on which the yarn is received as spun, detachably fitting at its lower

end within the central chamber of the said whirl part for the spinning operation and adapted to be removed therefrom with its load of yarn, substantially as described.

2. In combination, in a spinning-machine, 60 the rotating whirl part, the bearing in which the said whirl part is permanently mounted, and the wooden skewer on which the yarn is received as spun applied to the said whirl part during the spinning operation, and adapted 65 to be detached therefrom when the said yarn load, has been completed, substantially as described.

3. In combination, in a spinning-machine, 70 the rotating whirl part, a bearing with which the said whirl part remains permanently connected, and the double-ended or reversible skewer on which the yarn is received as spun connected with the said rotating whirl part during the operation of spinning and adapted 75 to be detached therefrom when its yarn load is completed, substantially as described.

4. In combination, in a spinning-machine, 80 the rotating whirl part having the internal bore and the groove forming a vent for air, and the skewer on which the yarn is received as spun fitting within the said bore and detached therefrom when the load of yarn has been completed, substantially as described.

5. A solid yarn-skewer for spinning, &c., 85 having the main length thereof shaped to contain a load of yarn wound thereon in the spinning operation, and having the end thereof shaped to enter and fit detachably the socket of a rotating whirl, substantially as described. 90

6. A solid reversible yarn-skewer for spinning, &c., having the main length thereof shaped to contain a load of yarn wound thereon in the spinning operation, and having each 95 end thereof shaped to enter and fit the socket of a rotating whirl, substantially as described.

7. A yarn-skewer for spinning, &c., having the barrel-shaped body to contain a load of yarn wound thereon in the spinning operation, and having each end thereof shaped to enter and fit the socket of a rotating whirl, 100 substantially as described.

In testimony whereof we affix our signatures in presence of two witnesses.

WILLIAM H. GOLDSMITH.
STEPHEN M. HAMBLIN.
